LOOP REGULATING MECHANISM FOR FLAT
KNITTING MACHINES

Max C. Miller, Cumberland, R. I.

Application September 21, 1938, Serial No. 230,971

31 Claims. (Cl. 66—82)

The present invention relates to flat knitting machines, and particularly to improvements in the loop regulating mechanism for such machines.

It is a principal object of the invention to provide novel and improved loop regulating mechanism for use in flat knitting machines of which the loop forming elements include knitting needles and associated sinkers and dividers, which is well adapted for automatic operation to effect a number of predetermined adjustments 10 of the stitch regulating mechanism during continued machine operation.

It is another object of the invention to provide in a machine of this general description, a loop regulating mechanism capable of producing automatic adjustments of loop length during knitting of the garment, which is well adapted to permit individual manual adjustment of each regulated position of the device during continued operation of the machine.

It is another object of the invention to provide a novel and improved loop regulating mechanism for use in machines of this general description, which is well adapted to effect an independent and extremely accurate positioning of the loop forming elements during each of the yarn sinking and dividing operations.

It is another object of the invention to provide a novel and improved stitch regulating mechanism adapted for automatic adjustment of stitch length during continued knitting on the machine, which will permit of a greatly increased versatility and adaptability of this mechanism to perform its desired functions in a modern automatic full-fashioned type machine, without at the same time sacrificing strength or compactness of organization, or accessibility of the mechanism for such manual adjustments as may be desirable or necessary in setting up and in actual operation of the machine.

With these and other objects in view, as may hereinafter appear, the several features of the invention consist in the devices, combinations and arrangement of parts hereinafter described and claimed, which together with the advantages to be obtained thereby will be readily understood from the following description taken in connection with the accompanying drawings, in which Fig. 1 is a cross-sectional view looking from the left, of a flat full-fashioned type knitting machine, only so much of the machine having been shown as is believed necessary to clearly illustrate the connection of the present invention therewith; Fig. 2 is a detail view looking from the left, illustrating particularly the yarn

sinking and divide loop regulating and needle press cams and associated rollers; Fig. 3 is a detail sectional view taken on the line 3—3 of Fig. 6, illustrating particularly the loop regulating cam drum for positioning the needles during the divide operation; Fig. 4 is a detail view in front elevation of the selector drum shown in Fig. 3; Fig. 5 is a detail sectional view taken on the line 5—5 of Fig. 6; Fig. 6 is a somewhat fragmentary view in front elevation illustrating three knitting sections of the machine, and applicant's improved loop regulating mechanism associated therewith; Fig. 7 is a large view in rear elevation of the yarn sinking, loop regulating mechanism shown in front elevation in Fig. 6; Fig. 8 is a sectional view taken on the line 8—8 of Fig. 7, the parts being shown in the position of Fig. 1; Fig. 9 is a somewhat diagrammatic view of the parts shown in Fig. 8 but with the lever sections 20 of the yarn sinking regulator lever separated during the divide operation; Fig. 10 is a somewhat diagrammatic sectional view of the lever sections of the divide loop regulator lever in operating position during the divide; Fig. 11 is a detail view of the drum rotating mechanism associated with the yarn sinking, loop regulating device, the parts being in the position shown in Fig. 1; Fig. 12 is a detail view in side elevation of the automatic drum racking control including 25 specifically the pawl and pawl shield for controlling the yarn sinking, loop regulating device, the parts being shown in the positions illustrated in Fig. 1; and Fig. 13 is a detail sectional view looking from beneath, of the drum holding spring 30 plunger associated with the yarn sinking loop regulating device shown in Figs. 1 and 6.

The stitch regulating mechanism herein disclosed in the drawings as embodying in a preferred form the several features of the invention, follows in a general way the usual organization 40 of the stitch regulating mechanism of these machines including a regulator shaft extending along the length of the machine, for controlling the positions of the needle forward and back motion cam levers, and cam actuated stitch adjusting levers consisting of a cam actuated lever section loosely mounted on the regulator shaft and a lever section adjustable relatively thereto 45 fixed to the shaft. Regulation of stitch length is obtained by mechanism which operates to relatively adjust the angular positions of the sections of the stitch regulating cam lever above referred to. In carrying out the present invention, applicant has succeeded in preserving the 50 advantageous features of strength, compactness 55

and accessibility inherent in the usual regulating mechanism, while at the same time through improvement in construction and in mode of operation, has succeeded in greatly increasing the versatility and adaptability of this mechanism to perform the desired functions in modern automatic full-fashioned type machines.

One feature of applicant's novel construction consists in the construction and arrangement of the mechanism for adjusting the relative positions of the lever sections which comprises a horizontally disposed drum supported on the cam actuated lever section loose on the regulator shaft, and a plurality of separately adjustable stop screws supported on the lever section secured to the regulator shaft for selective engagement with stop members spaced axially along the drum, and at different radial angles, so that a plurality of predetermined adjustments may be secured by the rotation of the drum to bring any selected stop screw into engagement with its co-operating stop member. This specific construction hereinafter more fully to be described, has the specific advantage of providing a plurality of predetermined adjusted positions of the regulating mechanism which are readily controlled through pattern operated selecting mechanism, while at the same time permitting the operator during continued knitting to effect such additional adjustment or correction in the position of any one or more of the stop screws as may be desirable or become necessary during continued operation of the machine.

Another feature of the invention consists in the construction and arrangement of an automatic stitch regulating mechanism which includes means for securing a number of predetermined adjustments of the stitch mechanism during continued machine operation, in combination with additional means which may be rendered operative to secure a gradual change in the stitch adjustment during the knitting of a number of following courses whereby the length of loop of following courses in the knitting of selected portions of the fabric, may be gradually changed to produce a desired shaping effect in the finished fabric.

Another feature of applicant's improved stitch adjusting mechanism, consists in the improved construction and arrangement of the actuating devices for controlling the position of and for shifting the loop regulating devices from one position of adjustment to another to cause the contacting surfaces of the stop screws and associated stop members to be moved directly away from each other while the adjustment is being effected, thus entirely obviating the possibility of wear upon these surfaces, with consequent loss of accuracy and precision in the device.

In the illustrated embodiment of the invention, this relative separating movement is secured by means of a specially shaped adjusting cam which permits the movable cam engaging section of the lever to be moved relatively inwardly or rearwardly from the section of the adjusting lever secured to the regulator shaft to avoid any possibility of interference with the movements of the forward and back motion needle cam lever under the influence of the needle in-and-out motion knitting cam.

Another feature of the invention consists in the specific arrangement of a racking mechanism for the selector drum supported on the movable cam actuated section of the stitch adjusting lever, and of pattern control devices therefor to cause

a positive racking of the drum to be effected in timed relation to the main cam shaft 20 of the machine which is entirely independent of the forward and back motions imparted to the 5 stitch adjusting lever and selector drum supported thereon. Mechanism adapted to this end is provided which includes a pattern cam shaft arranged to be given a step-by-step advancing movement in timed relation to the main cam shaft of the machine, and a pawl shield which is rendered operative for a limited period only, during each racking movement of the pattern shaft to permit the engagement of the drum ratchet with its actuating pawl.

Another feature of the invention consists in the provision of separate stitch adjusting mechanisms for controlling the forward and back positions of the needles during each of the yarn sinking and dividing operations, in which each of the adjusted positions of the two mechanisms is capable of independent and extremely accurate adjustment in setting up the machine, and subsequently during machine operation if found desirable. Applicant is aware that previous attempts have been made to produce stitch regulating mechanisms having means to secure a different adjustment of the needle position during each of the yarn sinking and dividing operations. Such constructions have, however, been found inadequate to avoid the formation of vertically striped fabric, due to the fact that the amount which it is necessary or desirable to back off the needles during the divide, varies with different types of yarn having different stretch and frictional characteristics. With the present construction, the operator is enabled to set each of the yarn sinking and divide stitch adjustments at any desired ratio, and is further able very quickly to correct any tendency to the formation of striped or sleazy fabric by further manual adjustment of the divide stitch regulating mechanism during machine operation.

In accordance with another feature of the invention, applicant provides pattern control mechanism which in the illustrated embodiment of the invention comprises the longitudinally extending pattern shaft above referred to, to permit simultaneous automatic adjustment of the yarn sinking and divide stitch regulating mechanisms during continued knitting on the machine.

Another feature of the invention consists in the specific arrangement of the adjustable stops associated with each of the yarn sinking and divide stitch regulating mechanisms to facilitate a rapid, if approximate, manual adjustment of each adjusted position of the two mechanisms in a direct ratio of 2 to 1. To this end the screw threads of the adjustable stops associated with the divide stitch regulating devices, are constructed with a pitch equal to one-half of that of the adjustable stops associated with the sinking stitch regulating device, so that the same angular adjustment may be made to each of the adjustable stops referred to, to secure an approximately equivalent adjustment of the two devices. It will be understood that alternative devices may be employed for the guidance of the operator in effecting a roughly equivalent adjustment of the corresponding stops associated with the yarn sinking and divide stitch regulating mechanisms, as for example, scale markings or notches on the stops or adjacent supporting surfaces.

The drawings disclose a flat full-fashioned knitting machine which may be of ordinary de-

scription comprising a series of transverse frames 10 spaced along the length of the machine, and rigidly connected by means of a longitudinally extending lower front rail 12, a lower back rail 14, a sinker rail 16, and a work table 18. The several cooperating mechanisms of the machine are driven from a main cam shaft 20 which extends along the machine length, and is continuously driven during the operation of the machine.

The knitting instrumentalities of the machine comprise the usual spring beard needles 22 supported in the needle beds 24 for vertical and forward and back movements with relation to a fixed press edge formed on the sinker bed 26, the yarn measuring sinkers 28, and alternating dividers 30 supported to slide in slots formed in the sinker bed 26 and cover plate 32. It may be assumed also that the machine is provided with the usual cooperating knockover bits (not shown). As best shown in Figs. 1 and 6, the needle bars 24 for the several sections of the machine, are pivotally supported on horizontally disposed levers 34 rigidly secured to a needle vertical motion rock shaft 36 extending throughout the machine length. Downwardly extending cam levers such as that designated at 38 are secured to the rock shaft 36 at intervals along the length of the machine, and are provided at their lower ends with rollers 40 for engagement with the usual needle vertical motion stitch and narrowing cams 42 and 44.

For imparting the usual forward and back movements to the needles, there is secured to each needle bar 24, a downwardly extending arm 46 which is connected by a horizontally disposed link 48 with a downwardly extending lever arm 50 secured to the usual needle forward and back motion rock shaft 52. Also secured to the rock shaft 52 at intervals along its length, are downwardly extending cam levers commonly referred to as the needle presser levers such as that designated at 54 which carries a roller 56 for engagement with the usual needle forward and back motion stitch cam 58 and narrowing cam 60.

In accordance with the usual construction and mode of operation of these machines, the yarn measuring sinkers 28 alternating with dividers 30, are individually movable, being advanced in the form of a knitting wave to kink the yarn against the shanks of the needles through the operation of sinker jacks 62 and a slur cock cam 64 carried on a reciprocating slide bar 66 for traversing movement along the length of the knitting section. With the construction illustrated, the yarn is kinked across each pair of needles by the alternately spaced sinkers, and is subsequently re-kinked or measured against all of the needles by the simultaneous advance of the dividers 30.

The machine is also provided with the usual catch bar motion including a catch bar 68 which is employed for simultaneously advancing the dividers, and subsequently for retracting the dividers and sinkers as the needles are moved to their press position, and then downwardly to draw the newly kinked yarn off the sinker noses. As best shown in Fig. 1 of the drawings, the catch bar is supported on rearwardly extending arms 70 pivotally supported on upwardly extending lever arms 72 secured to the catch bar forward and back motion rock shaft 74 extending along the length of the machine. Also secured to the rock shaft 74 are one or more downwardly

extending cam levers 76 such as that shown at 76 provided with roller 78 for engagement with a cam 80 on the cam shaft 20 of the machine.

5 The catch bars 68 are given the usual vertical motions to bring the catch bar into and out of operative engagement with the sinker butts through connections which include forwardly extending arms 82 secured to the catch bar 68 and supported at their forward ends on vertically extending links 84 and lever arms 86 secured to the catch bar vertical motion rock shaft 88 which extends along the length of the machine. Also secured to the rock shaft 88 are one or more cam levers such as that designated at 90 which carries a cam roller 92 for engagement with a cam 94 on the cam shaft 20 of the machine.

10 The stitch regulating mechanism disclosed in the drawings, consists in a stitch regulating rock shaft 100 of ordinary description which extends 20 along the front side of the machine, and is supported in bearings in the cross frames 10. At spaced intervals along its length, there are secured to the regulator shaft, upwardly extending lever arms such as that designated at 102 which are arranged for engagement behind contact rollers as shown at 104 formed on downward extensions of the needle forward and back motion levers 54.

15 In carrying out the present invention, applicant has provided two separate but substantially identical stitch regulating mechanisms for controlling the angular position of the regulator shaft 100 to properly position the needles 22 during each of the yarn sinking and subsequent divide operations, each comprising a stitch regulating lever made up of two relatively adjustable sections, and arranged to be acted upon by a stitch adjusting cam on the main cam shaft of the machine. For convenience, the stitch regulating mechanism for determining the needle position during the yarn sinking operation, will be first described, this mechanism being shown at the left side of Fig. 6, and in full lines in Figs. 1, 7 and 8 of the drawings. The yarn sinking 20 stitch adjusting lever consists of the so-called adjusting lever section 106 rigidly secured to the stitch regulator shaft 100 and a cooperating cam lever section 108 forked at its lower end to straddle the adjusting lever section 106, and provided at its upper end with a cam roller 110 for engagement with a yarn sinking stitch adjustment cam 112 on the main cam shaft 20 of the machine. The cam lever section 108 is loosely mounted to turn on the loop regulating shaft 100, and is supported with the roller 110 in engagement with a cam 112 by means of a tension spring 114. The secured section 106 of the yarn stitch sinking regulating lever secured to the regulator shaft 100 has supported thereon five adjustable stop pins 116 screw-threaded into the lever section 106, and arranged for engagement with cooperating segmental stop members on a horizontally disposed selector drum 118 supported in bearings formed on the movable cam lever section 108 of the stitch adjusting lever. In order to maintain the stop screws 116 in their adjusted positions, each of these stop screws is screw-threaded also to a spring clip 120 screw-fastened to the secured section 106 of the stitch adjusting lever. A rearwardly extending arm 117 formed on the secured lever section 106, has attached thereto a heavy tension spring 119 which acts to tension the lever section 106 and regulator shaft 100 rearwardly or in a counter-clockwise direction as viewed in Fig. 8 to main-

tain the stop screws 116 in engagement with the stop members formed on the drum 118. This rearward rocking movement of the fixed lever 106 and the regulator shaft 100, is limited by the engagement of a stop screw 121 on a downwardly extending arm of the lever 106 with the lower front rail 12 of the machine.

The stitch adjusting lever for determining the needle position during the yarn divide operation, similarly comprises a lever section 122 secured on the regulator shaft 100, and a relatively movable cam lever section 124 forked at its lower end to straddle the secured lever section 122, and provided at its upper end with a cam roll 126 for engagement with a yarn divide stitch adjustment cam 128 on the main cam shaft 20 of the machine. A spring 129 connected to a rearwardly extending arm of the cam lever section 124 tends to maintain the roller 126 in engagement with its cam 128. The secured lever section 122 is provided with five stop elements in the form of adjustable stop screws 130 screw-threaded thereto, and spring clips 132 for supporting the stop screws in adjusted position. The stop screws 130 are arranged to cooperate with cooperating segmental stop members formed on a horizontally disposed selector drum 134 supported on the movable cam lever section 124. The parts of the sinking and dividing stitch regulating levers thus far described, are identical in every respect, except that the adjustable screw stops 116 have twice the pitch of the adjustable screw stops 130, so that the operator is enabled to produce a corresponding adjustment of the respective yarn sinking and yarn divide stitch regulating positions by turning the corresponding stops through an identical angle. A tension spring 136 secured to a rearward extension of the secured lever section 122, tends to rock the lever section 122 and regulator shaft 100 rearwardly. A screw stop 138 mounted on a downward extension of the lever section 122 is arranged for engagement against the rail 12 to limit such rearward movement.

As best shown in Figs. 3 and 4 of the drawings, the selector drum 134 has supported along the length thereof, four segmental stop members 140 having peripheral contact surfaces of constant radius which are mounted in different angular positions on the drum to cooperate with the four left hand stops 130 as viewed in Fig. 6, and an additional stop member 142 arranged to cooperate with the right hand stop 130 as viewed in Fig. 6, and of which the contact surface is cammed to provide a gradual rising contour. The stop member 142 is supported on a friction pivot 144 on the right hand end of the selector drum, and is held in the desired adjustable position by means of a screw stop 146. The selector drum 118 associated with the yarn sinking loop regulating lever is identical in construction, having mounted thereon four fixed segmental stop members 148 spaced along the length of the drum, and supported at different angular positions for cooperating engagement with the left four adjustable stops 116, and a fifth adjustable stop member 150 having the contacting surface cammed gradually outward for engagement with the right hand screw stop 116 as viewed in Fig. 6.

It will readily be seen from an inspection of Fig. 3, that the adjustable stop member 142 on the divide regulator selector drum 134 and the identical stop member 150 on the yarn sinking regulator selector drum 118 are formed with rel-

atively long gradual rise surfaces, so that each racking of the drum as hereinafter more fully described, will cause the cooperating right hand stops 130 and 116 when in contact therewith, 5 to be very gradually moved outwardly to effect a correspondingly gradual change in stitch adjustment over a large number of following courses. While no specific illustration thereof has been made, it will be understood that for any particular adjustment of stop members 142 and 150, the stop member 150 of the yarn sinking stitch adjusting lever will have a total rise which is preferably double or substantially double to that of correspondingly adjusted stop member 142 of 10 the divide stitch adjusting lever. It will also be noted that the four segmental stop members 140 and the adjustable stop member 142 mounted on the drum 134 at different radial angles, are provided with contact surfaces which are of sufficient length so that a selected one or other of 15 said stop members will always be in position to cooperate with its cooperating screw stop pin irrespective of the angular position of the drum. Similarly, the contact surfaces of the segmental 20 stop members 148 and adjustable stop member 150 are arranged to completely occupy adjacent sectors of the selector drum 118. A selected one or other of these stop members will at all times be maintained in operative relationship to its 25 cooperating screw stop pin. It is contemplated that a number of successive rackings may be imparted to the drums before the active stop members on the two drums are moved out of 30 cooperating relation to their associated screw stop pins, and the next following stop members and cooperating screw stop pins are brought into 35 active operation to effect a different adjustment of stitch length. With this construction and arrangement of the selector drums and their cooperating screw stop pins, a relatively small racking movement may be imparted to the selector drums during each knitting operation of the machine, it being necessary only to effect a predetermined 40 number of such rackings in order to produce the next succeeding adjustment of stitch length. Applicant's improved stitch regulating mechanism is capable of a much wider range of 45 automatic adjustment than devices known in the prior art, inasmuch as the step-by-step rackings 50 of the selector drums are employed to effect in succession a plurality of fixed adjustments of the stitch regulating mechanism, and are also employed in the knitting of a designated portion of the knitted fabric, to produce a gradual changing 55 adjustment of the stitch regulator mechanism to produce a corresponding variation of loop length in the knitting of following courses.

The mechanism for rotating the selector drum 118 associated with the yarn sinking loop regulator lever as best shown in Figs. 1, 6, 11 and 12 comprises a cam actuated pawl lever 154 pivotally supported on a shaft 156, and provided at its upper end with a cam roller 158 for engagement with an actuating cam 160 on the cam shaft 20. 60 A pawl 162 pivotally supported on lever 154 is arranged for engagement with a ratchet 166 secured to the left hand end of the drum 118, being urged into engagement therewith by means of a small tension spring 168 secured at one end to a tail of the pawl 162, and at its other end to the pawl lever 154. The drum 118 is held in each successive stepped position through the engagement of a spring-pressed plunger 165 (see Fig. 13) seated in a lug 167 on the cam lever section 70 75

108 with a ratchet 169 rigidly secured to the right hand end of the drum 118. An identical mechanism is provided for racking the selector drum 134 associated with the divide stitch regulating lever which comprises a cam actuated pawl lever 170 (see Fig. 6) supported on pivot shaft 156, an actuating cam 172, a pawl 174, and a ratchet 176 secured to turn with the drum 134. A spring-pressed plunger 173 supported on a lug 175 on the cam lever section 122, is arranged for engagement with a ratchet 177 on the right hand end of the drum 134 to maintain the drum in each successive stepped position. The drum racking cams 160 and 172 are identical in construction, and are arranged to impart advancing movement to the pawls 162 and 174 to rack the respective drums 118 and 134 only while the component sections of the two stitch regulating levers are in their separated positions.

The racking of the selector drums from the continuously reciprocating pawls 162 and 174, is automatically controlled through pattern mechanism including a pattern shaft 178 which is given a step-by-step rotational movement through connections which are driven from the main cam shaft of the machine, and are arranged to be thrown into and out of operation at selected times by the pattern chain of the machine. As best shown in Figs. 1, 6 and 12 of the drawings, the pattern shaft 178 extends along the front side of the machine, and is provided at its left hand end with a ratchet 180 which is arranged to be engaged by a pawl 182 pivotally supported on one arm of a cam lever 184 loosely mounted to turn on the regulator shaft 100. A rearwardly extending arm of the lever 184 carries a roller 186 for engagement with a cam 188 on the main cam shaft 20 of the machine. A small tension spring 190 connected at one end to the pawl 182, and at its other end to the cam lever 184, tends to maintain the pawl in operative engagement with the ratchet 180. The roller 186 is maintained in engagement with its cam by means of a tension spring 192 connected to the forwardly extending arm of the lever 184. The operation of the pawl 182 to advance the pattern shaft 178 is controlled from the main pattern chain of the machine diagrammatically indicated at 194 through connections which include a pawl shield 196 loosely mounted to turn on the pattern shaft 178. A forwardly extending arm of the shield 196 is connected by means of a short link 198 with one arm of a pattern chain lever 200 mounted on a stationary pivot shaft 202, and arranged to be acted upon by buttons such as that designated at 204 on the pattern chain 194. A small tension spring 206 connected between a tail portion of the pattern lever 200 and a fixed arm 208, tends normally to maintain the pattern lever in the depressed position shown in Figs. 1, 6 and 12, in which the shield 196 is in position to prevent the engagement of the actuating pawl 182 with the ratchet 180.

The racking movements imparted to the pattern shaft 178 are rendered operative to move the continuously reciprocating pawl 162 into and out of engagement with the ratchet 166 to advance the yarn sinking selector drum 118 through connections which include a rearwardly extending pawl shield lever 210 supported at its forward end on pivot shaft 212, and provided at its rear end with an upwardly curved pawl shield surface 214 for engagement with the pawl 162. A small tension spring 216 connected at one end to the

5 pawl lever 210 tends normally to maintain the pawl lever 210 in the low position shown in Figs. 1 and 12, in which the shield surface 214 is engaged with and holds the pawl 162 out of operative position. The operation of the pawl lever 210 is controlled by means of a cam disk 218 having formed therein one or more short rise portions or bumps 220 for engagement with a V-shaped abutment 222 on the under side of the pawl lever 210. The peripheral surface of the cam disk 218 provides a stop surface against which the pawl lever 210 is held under the influence of its spring 216 to hold the drum actuating pawl 162 in its inoperative position shown in Figs. 1 and 12. The operation of the pawl 174 for racking the selector drum 134 of the divide loop regulator device, is controlled from the pattern shaft 178 through connections which are similar to those previously described, and more fully illustrated in connection with the yarn sinking loop regulating mechanism, and include a pawl lever 224 which is supported on a rock shaft 212 and engages against a cam disk 226 on the pattern shaft 178 for controlling the position of the pawl 174, the pawl lever 224 being maintained in operative engagement with the disk 226 by means of a tension spring (not shown), but similar to that designated at 216. It will be understood that the cam disks 218 and 226 are identical in construction, and have similarly placed rise portions 220 thereon, so that the pawl levers 210 and 224 will always be operated simultaneously for moving their respective drum pawls 162 and 174 into and out of operative position.

35 It will be noted that the cam 188 through which the racking of the pattern shaft 178 is effected, is provided with a stepped rise portion, the first or lower rise portion being arranged to rack the pattern shaft 178 into a position in which the rise portions 220 of the cam disks 218 and 226 are brought beneath the corresponding abutments on the pawl levers 210 and 224 to permit movement of the drum actuating pawls 162 and 174 into operating position. It is while the cam roller 186 is riding on this first stepped portion of the cam 188, that the pawls 162 and 174 are given their racking movement by the operation of the pawl actuating cams 160 and 172. Continued rotation of the main cam shaft 20 40 then causes the roller 186 to ride into the higher stepped portion of its cam 188, further rotating the pattern shaft 178 to move the rise portions 220 from beneath the abutments on the pawl levers 210 and 224, thus disconnecting the drum actuating pawls 162 and 174 from their ratchets. With this construction and arrangement of the drum actuating mechanism, it will readily be seen that the drum actuating pawls 162 and 174 are permitted to be in operating engagement with their respective ratchets through a small portion only of the knitting cycle of the machine during which the sections of both regulating levers are separated, as hereinafter more fully set forth in connection with the description of the operation, 45 and during which the pawls 162 and 174 are being advanced to rack the drums cam lever sections with the drums supported thereon. Positioning movements imparted to the cam lever sections 108 and 124 during other portions of the knitting cycle therefore can have no effect to cause inadvertent or undesired racking of the drums.

70 The operation of applicant's improved loop regulating mechanism will be briefly described as follows:

During each knitting cycle of the machine, that is, during each revolution of the main cam shaft 20 the yarn carriers (not shown) together with the slur-cock cams 64 are traversed across the respective knitting sections of the machine, causing the yarn measuring sinkers 28 to be advanced in a knitting wave to sink yarn against the needle shanks. During the yarn sinking operation, the position of the needles is controlled by the yarn sinking, loop regulating mechanism. The position of the parts at this time, including particularly the needle in-and-out or press cam motion, the yarn sinking, loop regulating mechanism and the divide loop regulating mechanism, is that illustrated in Figs. 1, 2 and 8, in which the cam roller 110 is riding on the peripheral portion of the yarn sinking, regulating cam 112, and a screw stop pin 116 is in contact with the selected stop member 150 to determine the angular position of regulator shaft 100, and thereby the in-and-out yarn sinking position of the needles. At this stage of the loop forming cycle, the needle in-and-out motion roller 56 is supported out of contact with the circular portion of the needle in-and-out or press motion knitting cam 58. Also at this stage of the loop forming cycle, the divide loop regulating mechanism is inoperative. The divide loop regulating cam roller 126 is riding on the peripheral portion of its cam 128 and, as illustrated for example in Fig. 2, is in alignment with the yarn sinking, loop regulating cam roller 110. The lever sections of the divide loop regulating mechanism are, however, slightly separated since, by hypothesis, the stop screws 130 of the divide regulating device are adjusted to control the in-and-out position of the needles only during the divide, that is, for a position of the needles which is further removed from the press edge of the machine and are therefore at this time positioned out of contact with their cooperating stop members 140 or 142.

After the last jack sinker 28 has been projected, the dividers 30 alternating with the sinkers in accordance with the usual practice in full-fashioned machines are brought forth as a unit by the catch bar 68. The catch bar motion operates to advance the dividers against the usual verge plate, bringing the dividers and sinkers into alignment and causing yarn to be robbed from the loops previously formed by the yarn measuring sinkers to produce sinker loops of equal length between all the needles.

During the divide operation, in accordance with the present invention, the yarn sinking loop regulating mechanism is rendered inoperative and the divide loop regulating device is brought into operation to control the position of the needles to accord with the shorter loop length produced by the divide, that is, at a point further removed from the press edge of the machine. At the beginning of the divide operation, the cam roller 110 associated with the yarn sinking loop regulating device moves onto a cut-away portion 230 of its cam 112, thus permitting the cam lever section 108 to fall rearwardly under the influence of its spring 114 and permitting the regulator shaft 100 to rock rearwardly under the influence of springs 119 and 136 to a position which is now determined by the setting of the divide loop regulating device. The position of the cam lever section 108 at this point of the operation is illustrated in Fig. 9 of the drawings. At this time, the cam roll 126 associated with the divide regulator device is riding onto the portion 232

of its cam 128 which is relatively higher than the cut-away portion 230 of the yarn sinking regulator cam 112. The exact position assumed by the needles during the divide is now determined by the contact of the active one of the screw stop pins 130 with its cooperating stop 140 or 142. In the position shown in the drawings and more particularly in Fig. 10, the right-hand stop pin 130 is in engagement with the stop member 142 on the drum 134. It will be noted, as best shown in Fig. 2 of the drawings, that the needle press cam 58 is also provided at this point with a cut-away portion 234 so that the needle press roller 56 is still maintained out of contact therewith.

During the continued rotation of the cam shaft 20, the needles move downwardly and rearwardly to press. It will be noted that each of the stitch regulating cams 128 and 112 is provided with outward projections having the same shape as the press projection of the needle press cam 58. The needle motion is, however, at this time taken over by the needle cam 58.

The needle in-and-out motion is from this point controlled in the usual manner by the needle in-and-out motion cam 58 to cause the needles to operate in the usual manner during the drawing down of the sunk loops and the return movement of the needles to their high yarn sinking position. During continued rotation of the cam shaft 20, the regulator rollers 126 and 110 are permitted to ride inwardly on cutaway portions 238 (see Fig. 2). These cutaway portions are of sufficient depth, so that the movable lever sections 124 and 108 are permitted to move rearwardly a sufficient distance to disengage the cam drums 134 and 118 respectively, from the adjustable stops on the fixed lever sections 122 and 106, which move inwardly also under the influence of springs 119 and 136 to a limiting position determined by the engagement of adjustable stops with the front rail 12 of the machine. While the regulator lever sections are in this separated position, the racking of the drums 134 and 118 is effected as above described.

It will be understood that the invention is not limited to the specific embodiment shown, and that various deviations may be made therefrom without departing from the spirit and scope of the appended claims.

What is claimed is:

1. In a knitting machine having loop forming elements including knitting needles and associated sinkers and dividers operable in accordance with a loop forming cycle, and loop regulating means coacting with said loop forming elements for producing fabric loops of predetermined length, said loop regulating means comprising separately adjustable devices successively operable in said loop forming cycle for positioning the loop forming elements during each of the yarn sinking and divide operations.

2. In a knitting machine having loop forming elements including knitting needles and associated sinkers and dividers operable in accordance with a loop forming cycle, loop regulating means coacting with said needles for producing fabric loops of predetermined length, said loop regulating means comprising separately adjustable devices successively operable in said loop forming cycle for positioning the needles during each of the yarn sinking and divide operations.

3. In a knitting machine having knitting needles and associated loop forming sinkers and dividers operable in accordance with a loop form-

ing cycle, loop regulating mechanism comprising a loop regulating cam and loop regulating means associated therewith for positioning the needles during the yarn sinking operation, and a second loop regulating cam and loop regulating means associated therewith for positioning the needles during the divide operation.

4. In a knitting machine having loop forming elements including knitting needles and associated sinkers and dividers operable in accordance with a loop forming cycle, and loop regulating means coacting with said loop forming elements for producing fabric loops of predetermined length, said loop regulating means comprising separate devices successively operable in said loop forming cycle for positioning the loop forming elements during each of the yarn sinking and divide operations, each of said devices having a plurality of manually adjustable elements successively operable to determine the position of the loop forming elements.

5. In a knitting machine having loop forming elements including knitting needles and associated sinkers and dividers operable in accordance with a loop forming cycle, and loop regulating means coacting with said loop forming elements for producing fabric loops of predetermined length, said loop regulating means comprising separate devices successively operable in said loop forming cycle for positioning the loop forming elements during each of the yarn sinking and divide operations, each of said devices having a plurality of manually adjustable elements and a shiftable member associated therewith to render said adjustable elements successively operable to determine the position of the loop forming elements.

6. In a knitting machine having loop forming elements including knitting needles and associated sinkers and dividers operable in accordance with a loop forming cycle, and loop regulating means coacting with said loop forming elements for producing fabric loops of predetermined length, said loop regulating means comprising separate devices successively operable in said loop forming cycle for positioning the loop forming elements during each of the yarn sinking and divide operations, each of said devices having a plurality of predetermined adjustments, actuating means for rendering said adjustments successively operative to determine the position of the loop forming elements, and means for simultaneously actuating the actuating means associated with said devices.

7. In a knitting machine having loop forming elements including knitting needles and associated sinkers and dividers operable in accordance with a loop forming cycle, and loop regulating means coacting with said loop forming elements for producing fabric loops of predetermined length, said loop regulating means comprising separate devices successively operable in said loop forming cycle for positioning the loop forming elements during each of the yarn sinking and divide operations, each of said devices having a plurality of manually adjustable elements and a shiftable member associated therewith to render said manually adjustable elements operable to determine the position of the loop forming elements, means for effecting a simultaneous movement of said shiftable members, and pattern means for dictating the operation of said last-mentioned means.

8. In a knitting machine having knitting needles and associated loop forming sinkers and

dividers operable in accordance with a loop forming cycle, loop regulating mechanism comprising a loop regulating cam and loop regulating means associated therewith having a plurality of adjusted positions for positioning the needles during the yarn sinking operation, a second loop regulating cam and loop regulating means associated therewith having a plurality of adjusted positions for positioning the needles during the divide operation in said cycle, and means for simultaneously shifting both of said regulating means from one to another of said adjusted positions to effect a corresponding adjustment of the needle position for each of said yarn sinking and divide operations.

9. In a knitting machine having a cam shaft and knitting devices including knitting needles and associated loop forming sinkers and dividers operable in accordance with a loop forming cycle, the combination with a needle bar presser lever and an operating shaft, a loop regulating mechanism for producing individual adjustments during the yarn sinking and divide operations in said cycle comprising with a regulating shaft and a stop arm for said presser lever fixed to said shaft, separate loop regulating devices for controlling the position of said stop arm for producing successive individual adjustments of the presser lever during the yarn sinking and divide operations in said cycle, each regulating device comprising a cam on the cam shaft, a cam operated loose arm on the regulating shaft, and a rocker arm secured to the regulating shaft, a rotating drum having a plurality of stop members thereon and a plurality of adjustable stops supported for relative engagement on said loose arm and secured rocker arm respectively, and means for simultaneously rotating said drums to effect a simultaneous adjustment of said sinker and divide loop regulating devices.

10. In a knitting machine having a cam shaft and knitting devices including knitting needles and associated loop forming sinkers and dividers operable in accordance with a loop forming cycle, the combination with a needle bar presser lever and an operating shaft, a loop regulating mechanism for producing individual adjustments during the yarn sinking and divide operations in said cycle comprising a regulating shaft, a stop arm for said presser lever fixed to said shaft, and separate loop regulating devices for controlling the position of said stop arm for producing successive individual adjustments of the presser lever during the yarn sinking and divide operations, each comprising a cam on the cam shaft, a cam operated loose arm on the regulating shaft, and a rocker arm secured to the regulating shaft, a rotating drum having a plurality of stop members spaced axially and at different radial angles thereon and a plurality of adjustable stop elements supported for relative engagement, said drum and adjustable stop elements being mounted on said loose arm and secured rocker arm respectively, means for simultaneously rotating said drums to effect a simultaneous adjustment of said sinker and divide loop regulating devices, and pattern means for dictating the operation of said drum rotating means.

11. The combination with a variable stitch regulating means of a knitting machine, which includes a composite lever structure comprising a pair of lever sections, a horizontally disposed rotatable drum, and a plurality of horizontally spaced stop elements carried by said lever sections for varying the angle between said lever

sections, a plurality of stop members spaced axially on said drum and at different radial angles for successive engagement each with a cooperating stop element, certain of said stop members having peripheral contact surfaces, and at least one of said stop members having a peripherally disposed gradual rise cam stop surface for engagement with a cooperating stop element, means for intermittently rotating said cam drum in one direction, and pattern means for dictating the operation of said drum rotating means.

12. The combination with a variable stitch regulating means of a knitting machine which includes a composite lever structure comprising a pair of lever sections, a rotatable drum and a plurality of horizontally spaced adjustable stop elements carried by said lever sections for varying the angle between said lever sections, a plurality of stop members having peripheral cam stop surfaces spaced axially on said drum and at different radial angles for successive engagement each with a cooperating stop element, one of said stop members having a peripherally disposed gradual rise cam stop surface for engagement with a cooperating stop element, and means for intermittently rotating said cam drum in one direction.

13. The combination with a variable stitch regulating means of a knitting machine which includes a composite lever structure comprising a pair of lever sections, a rotatable supporting member and a cam engaging stop element carried by said lever sections for varying the angle between said sections, and including a stop member movably supported on said rotatable supporting member and having a peripherally disposed gradual rise cam stop surface for engagement with said stop element, means for adjusting said stop member to vary the angle of rise, and means for intermittently rotating said supporting member in one direction for gradually varying the angle between said lever sections in the knitting of successive courses, thereby producing a correspondingly gradual variation in the length of stitch produced by said machine.

14. In a knitting machine having knitting needles and associated loop forming sinkers and dividers operable in accordance with a loop forming cycle, variable stitch regulating devices for producing a separate adjustment of said needles for each of the sinking and divide operations in said cycle, each of said devices including a composite lever structure comprising a pair of lever sections, a rotatable supporting member and a cam engaging stop element carried by said lever sections for varying the angle between said sections, and including a stop member on said supporting member having a peripherally disposed gradual rise cam stop surface for engagement with said stop element, and means for simultaneously turning each of said supporting members intermittently in one direction for effecting successive adjustments of the angle between each pair of lever sections in the knitting of successive courses thereby producing corresponding gradual variations of the needle positions for each of said sinking and divide operation.

15. In a knitting machine having knitting needles and associated loop forming sinkers and dividers operable in accordance with a loop forming cycle, variable stitch regulating devices for producing successively a separate adjustment of said needles for each of the sinking and divide operations, each of said devices including a composite lever structure comprising a pair of lever

sections, a rotatable drum and a plurality of horizontally spaced stop elements carried by said lever sections for varying the angle between said sections, a plurality of stop members spaced axially on said drum and at different radial angles for successive engagement each with a cooperating stop element, certain of said stop members having contacting surfaces of constant radius, and at least one of said stop members associated

10 with each drum having a peripherally disposed gradual rise portion, and means for simultaneously turning each of said drums intermittently in one direction, and pattern means for dictating the operation of said drum turning means.

15 16. The combination with variable stitch regulating means of a knitting machine which includes a composite lever structure comprising a pair of lever sections, a drum rotatably supported on one of said lever sections, a plurality of adjustable stop elements cooperating with said drum carried by the other of said sections for varying the angle therebetween, a plurality of fixed stop surfaces spaced axially along the drum and at different radial angles thereon for successive engagement each with a respective stop element, and an adjustable stop member on the drum having a gradually rising contour surface extending about the periphery of said drum for engagement with one of said stop elements, and means for adjusting said stop member to adjust the angle of rise of said contour surface.

20 25 30 35 40 45 50 55 60 65 70 75 17. The combination with variable stitch regulating means of a knitting machine which includes a composite lever structure comprising a pair of lever sections, a drum rotatably supported on one of said lever sections, a plurality of adjustable stop elements cooperating with said drum carried by the other of said lever sections for varying the angle therebetween, a plurality of stop members spaced axially on the drum and at different radial angles thereon, for successive engagement each with a respective stop element, and including, an adjustable stop member on the drum having a gradually rising contour surface extending about the periphery of said drum for engagement with one of said stop elements, means for adjusting said adjustable stop member to adjust the angle of rise of said contour surface, racking means for imparting a step-by-step rotating movement to the drum, and pattern control means for dictating the operation of said racking means to turn the drum.

18. In a knitting machine having a cam shaft, knitting needles and associated loop forming sinkers and dividers operable in accordance with a loop forming cycle, and loop stitch regulating mechanism for effecting successive separate adjustments of the needles for each of the sinking and dividing operations in said loop forming cycle comprising a pair of yarn sinking and divide loop regulating cams on said cam shaft, a loop regulating shaft, and adjustable loop regulating devices associated with each of said loop regulating cams and the loop regulating shaft, means actuated from said cam shaft for effecting an adjustment of each of said loop regulating devices, a pattern shaft, and means controlled from the pattern shaft for simultaneously throwing said adjusting means into and out of operation.

19. For use in a flat knitting machine having a cam shaft and knitting devices including knitting needles and yarn measuring sinkers cooperating therewith, a stitch regulating mechanism which comprises a loop regulator shaft, a

composite loop regulator lever structure including a cam lever section loosely mounted to turn on the regulator shaft, a lever section secured to turn with the regulator shaft, a horizontally disposed drum rotatably mounted on said cam lever section above the regulator shaft, a plurality of horizontally spaced adjustable stop elements on the fixed lever section, a plurality of peripheral stop surfaces spaced lengthwise of the drum and in different angular positions thereon for successive engagement each with a cooperating stop, means for rotating the drum, and means effective during said rotating movement for relatively separating said cam lever sections to disengage said stop elements from the stop surfaces.

20. For use in a flat knitting machine having a cam shaft and knitting devices including knitting needles and yarn measuring sinkers cooperating therewith, a stitch regulating mechanism which comprises a loop regulator shaft, a composite loop regulator lever structure including a cam lever section loosely mounted to turn on the regulator shaft, a lever section secured to turn with the regulator shaft, a horizontally disposed drum rotatably mounted on said cam lever section above the regulator shaft, a plurality of horizontally spaced adjustable stop elements on the fixed lever section, a plurality of peripheral stop surfaces spaced lengthwise of the drum and in different angular positions thereon for successive engagement each with a cooperating stop element, racking means for rotating the drum, a cam on the cam shaft for actuating said racking means, and means effective during said racking movement for relatively separating said cam lever sections to disengage said stop elements from the stop surfaces.

21. For use in a flat knitting machine having a cam shaft and knitting devices including knitting needles and yarn measuring sinkers cooperating therewith, a stitch regulating mechanism which comprises a loop regulator shaft, a composite loop regulator lever structure including a cam lever section loosely mounted to turn on the regulator shaft, a lever section secured to turn with the regulator shaft, a horizontally disposed drum rotatably mounted on said cam lever section above the regulator shaft, a plurality of horizontally spaced adjustable stop elements on the fixed lever section, a plurality of peripheral stop surfaces spaced lengthwise of the drum and in different angular positions thereon for successive engagement each with a cooperating stop element, racking means for rotating the drum, a cam on the cam shaft for actuating said racking means, and means effective during said racking movement for relatively separating said cam lever sections to disengage said stop elements from the stop surfaces, and pattern means for rendering said racking means operative and inoperative to rack the drum.

22. For use in a flat knitting machine having a cam shaft and knitting devices including knitting needles and yarn measuring sinkers cooperating therewith, a stitch regulating mechanism which comprises a loop regulator shaft, a composite loop regulator lever structure including a cam lever section loosely mounted to turn on the regulator shaft, a lever section secured to turn with the regulator shaft, a horizontally disposed drum rotatably mounted on said cam lever section above the regulator shaft, a plurality of horizontally spaced adjustable stop elements on the fixed lever section, a plurality of peripheral

stop surfaces spaced lengthwise of the drum and in different angular positions thereon for successive engagement each with a cooperating stop element, racking means for rotating the drum, and means effective during said racking movement for relatively separating said cam lever sections to disengage said stop elements from the stop surfaces, a cam on the cam shaft for actuating said racking means, a pattern shaft, connections controlled thereby for rendering said racking means operative and inoperative to rack the drum, means for rotating the pattern shaft, and a pattern chain and connections therefrom for dictating the movement of the pattern shaft.

23. For use in a flat knitting machine having a cam shaft and knitting devices including knitting needles and yarn measuring sinkers cooperating therewith, a look regulating mechanism which comprises a loop regulator shaft, a composite loop regulator lever structure including a cam lever section loosely mounted to turn on the regulator shaft, a lever section secured to turn with the regulator shaft, automatically operable means for effecting successive adjustments of the loop regulating mechanism comprising successively contacting pairs of regulating stop surfaces on said lever sections, and means for positioning successive pairs of stop surfaces in contacting position, a regulator cam on the cam shaft having a portion thereof cut away to permit rearward movement of the cam lever section from contacting position, means for tensioning the secured lever section rearwardly, stop means to limit rearward movement of the secured lever section to provide a separation between said lever sections, and means acting in timed relation to rotation of the cam shaft to effect the adjustment of said automatic adjusting means while said lever sections are in separated positions.

24. For use in a flat knitting machine having a cam shaft and knitting devices including knitting needles and yarn measuring sinkers cooperating therewith, a stitch regulating mechanism which comprises a loop regulator shaft, a composite loop regulator lever structure including a cam lever section loosely mounted to turn on the regulator shaft, a lever section secured to turn with the regulator shaft, a horizontally disposed drum rotatably mounted on said cam lever section above the regulator shaft, a plurality of horizontally spaced adjustable stop elements on the fixed lever section, a plurality of peripheral stop surfaces spaced lengthwise of the drum and in different angular positions thereon for successive engagement each with a cooperating stop element, a regulator cam on the cam shaft having a portion thereof cut away to permit a separating movement of the cam lever section from the secured lever section, racking means for the drum, and means actuated from the cam shaft for actuating said racking means while the lever sections are in said separated position.

25. For use in a flat knitting machine having a cam shaft and knitting devices including knitting needles and yarn measuring sinkers cooperating therewith, a loop regulating mechanism which comprises a loop regulator shaft, a composite loop regulator lever structure including a cam lever section loosely mounted to turn on the regulator shaft, a lever section secured to turn with the regulator shaft, a horizontally disposed drum rotatably mounted on said cam lever section above the regulator shaft,

a plurality of horizontally spaced adjustable stop elements on the fixed lever section, a plurality of peripheral stop surfaces spaced lengthwise of the drum and in different angular positions thereon for successive engagement each with a cooperating stop element, racking means for imparting step-by-step rotating movements to the drum, means effective during said racking movement for relatively separating said cam lever sections to disengage said stop elements from the stop surfaces, locking means for supporting the drum in each of said step positions, and pattern means for dictating the operation of said racking means.

26. For use in a flat knitting machine having a cam shaft and knitting devices including knitting needles and yarn measuring sinkers co-operating therewith, a stitch regulating mechanism which comprises a loop regulator shaft, a composite loop regulator lever structure including a cam lever section loosely mounted to turn on the regulator shaft, a lever section secured to turn with the regulator shaft, a horizontally disposed drum rotatably mounted on said cam lever section above the regulator shaft, a plurality of horizontally spaced adjustable stop elements on the secured lever section, a plurality of peripheral stop surfaces spaced lengthwise of the drum and in different angular positions thereon for successive engagement each with a co-operating stop element, a regulator cam on the cam shaft having a cut away portion to permit rearward movement of the cam lever section out of operative position with relation to the secured lever section, racking means for the drum, a cam on the cam shaft for actuating said racking means with the cam lever section in its separated position, a pattern shaft, means actuated from the pattern shaft to render said racking means operative and inoperative to rack the drum, and means including a double stepped cam on the cam shaft for imparting successive increments of rotation to the pattern shaft to render said racking means operative and inoperative only while the cam actuated lever section is in its separated position.

27. In a knitting machine having a cam shaft, knitting needles and associated loop forming sinkers and dividers operable in accordance with a loop forming cycle, and loop stitch regulating mechanism for effecting successive separate adjustments of the needles for each of the sinking and divide operations in said cycle, comprising a pair of yarn sinking and dividing loop regulating cams on said cam shaft, a loop regulating shaft, a composite loop regulating lever structure associated with each cam, each comprising a cam lever section loosely mounted to turn on the regulating shaft, a lever section secured to turn with the regulating shaft, a horizontally disposed drum rotatably mounted on said cam lever section, and a plurality of horizontally spaced adjustable stop elements on the fixed lever section, the stop elements associated with the divide regulating lever having means to facilitate a manual adjustment thereof which is proportionate to a similar manual adjustment of corresponding stop elements associated with the sinking regulating lever.

28. In a knitting machine having a cam shaft, knitting needles and associated loop forming sinkers and dividers operable in accordance with a loop forming cycle, and loop stitch regulating mechanism for effecting separate adjustments of the needles for each of the sinking and divide

operations in said loop forming cycle, comprising a pair of yarn sinking and dividing loop regulating cams on said cam shaft, a loop regulating shaft, a composite loop regulating lever structure associated with each cam, each comprising a cam lever section loosely mounted to turn on the regulating shaft, a lever section secured to turn with the regulating shaft, and cooperating stop surfaces and screw-threaded stop elements supported by said lever sections in which the screw threads of the stop elements associated with the divide regulating lever have a pitch equal to one-half of the pitch of the stop elements associated with the sinking regulating lever.

29. In a knitting machine having a cam shaft, knitting needles and associated loop forming sinkers and dividers operable in accordance with a loop forming cycle, and loop regulating mechanism for effecting successive separate adjustments of the needles for each of the sinking and divide operations in said loop forming cycle comprising a pair of yarn sinking and loop divide cams on said cam shaft, a loop regulating shaft, separate composite yarn sinking and divide loop regulating lever structures, each including a cam lever section loosely mounted to turn on the regulator shaft, a lever section secured to turn with the regulator shaft, and cooperating stop members and stop elements on said lever sections for determining the relative angular positions of the lever sections of each of said loop regulating lever structures, the divide loop regulating cam having the contour thereof shaped to position the associated cam lever section in inoperative position during the yarn sinking operation, and the yarn sinking loop regulating cam having the engaging surface thereof shaped to position the associated cam lever section in inoperative position during the divide operation.

30. In a knitting machine having a cam shaft, knitting needles and associated loop forming sinkers and dividers operable in accordance with a loop forming cycle, and loop regulating mechanism for effecting successive separate adjustments of the needles for each of the yarn sinking and divide operations in said loop forming cycle which comprises a pair of yarn sinking and divide loop regulating cams on said cam shaft, a loop regulating shaft, composite yarn sinking and divide loop regulator lever structures each including a cam lever section loosely mounted to turn on the regulator shaft, a lever section secured to turn with the regulator shaft, a horizontally disposed drum rotatably mounted on each of said cam lever sections, a plurality of horizontally spaced adjustable stop elements on each of the secured lever sections, a plurality of stop surfaces spaced lengthwise on each of the drums and in different angular positions thereon for engagement, each with a cooperating stop, means controlled from the cam shaft for simultaneously rotating said drums to effect an adjustment of said loop regulating mechanism, said divide regulating cam having the engaging surface thereof shaped to position the associated cam lever section in inoperative position during yarn sinking and during the rotation of the drum, and said yarn sinking regulating cam having the engaging surface thereof shaped to position the associated cam lever section in inoperative position during the divide operation and during the rotation of the drum.

31. In a knitting machine having loop form-

ing elements including knitting needles and associated dividers and sinkers operable in accordance with a loop forming cycle, and loop regulating means associated with said loop forming elements for producing fabric loops of predetermined length, said loop regulating means comprising separately adjustable devices successively operable in said loop forming cycle for positioning the loop forming elements dur-

ing each of the yarn sinking and dividing operations, each of said devices having a plurality of predetermined adjustments, actuating means for rendering said adjustments successively operative to determine the position of the loop forming elements during each of said sinking and dividing operations, and pattern means for dictating the operation of said actuating means.

MAX C. MILLER.
